UNITED STATES PATENT OFFICE.

JOHN L. LEWIS, OF PITTSBURG, PENNSYLVANIA.

IMPROVEMENT IN PILE OR FAGOT FOR SHOE-RAIL FOR GUN-CARRIAGES.

Specification forming part of Letters Patent No. 36,223, dated August 19, 1862.

To all whom it may concern:

Be it known that I, JOHN L. LEWIS, of Pittsburg, in the county of Allegheny and State of Pennsylvania, have invented a new and Improved Pile for Rolling Shoe-Rail for Gun-Carriages, &c.; and I do hereby declare that the following is a full, clear, and exact description of the same, reference being had to the accompanying drawings, making a part of my specification, in which—

Figure 1 represents a transverse vertical section of my invention. Fig. 2 is a side elevation of the same. Fig. 3 shows a section of the shoe-rail when rolled.

Similar letters of reference in the views indicate corresponding parts.

This invention consists in forming the pile of several flat bars of iron, two of which are about of equal width and placed in such a relative position to each other that they form an inverted T, the stem or vertical part of which is kept in position by two or more flat bars that are placed one or more on each side of said vertical part and on the top of the base, and the width of which is equal to one-half the width of the base less one-half the thickness of the vertical bar, the whole being arranged and combined in such a manner that ordinary bars of iron—such as are usually made and sold in the market—can be used for forming the pile without subjecting them to a preliminary rolling or other operation, and that by passing the pile once through suitable rollers finished shoe-rails are produced.

To enable others skilled in the art to make and use my invention, I will proceed to describe it with reference to the drawings.

My pile is formed of a series of flat bars, A B C', which are arranged in relation to each other as clearly shown in Fig. 1 of the drawings. The bar A, which forms the base of the pile, is fully as wide as the base of the intended shoe-rail is to be, and of any convenient thick-

ness less than the thickness of the intended rail. The bar B is placed edgewise exactly on the center of the bar A, so that the cross-section or end view of the two bars is similar to an inverted T. This bar is intended to form the vertical part or tread of the shoe-rail, and its thickness is about equal to the thickness of the tread to be formed, while its height or width exceeds that of said tread, as will be clearly understood by comparing Figs. 2 and 3 of the drawings.

Bars C C' are placed on the top of the bar A and on opposite sides of bar B, so that they steady the same in its position. The width of these bars is equal to one-half the width of the bar A less one-half the thickness of the bar B, and they, together with the bar A, form the base of the intended rail. The thickness of the bars C C' therefore is so selected that the same, together with bar A, contain sufficient iron to make up the base of the rail, and, if it should be desirable, two or more such bars might be placed, one on the top of the other, on either side of the bar B. Thus arranged, the pile is heated and passed through suitable rollers, and the shoe-rail is formed and finished in one operation.

It will be noticed that the bars which I use for my pile can be selected from such iron as is generally rolled out and sold in the market, so that no extra rolling is required in order to fit them for the pile.

Having thus fully described my invention, what I claim as new, and desire to secure by Letters Patent, is—

The manner herein shown and described of arranging or disposing the bars A B C C' in forming a pile, for the purpose set forth.

JOHN L. LEWIS.
